Primary Examiner — Carla Jobe Wright(74) *Attorney, Agent, or Firm* — Morgan, Lewis & Bockius LLP(57) **CLAIM**

The ornamental design for a case for cellular phone, as shown and described.

DESCRIPTION

FIG. 1 is a front, left side, perspective view of a case for cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, left-side perspective view thereof shown in a state of use with an unclaimed cellular phone.

The broken lines in FIGS. 3 and 6 depict an unclaimed feature of the case for cellular phone. In FIG. 8, the broken lines and the unshaded front surface bounded on two sides by broken lines and on two sides by solid lines depict an unclaimed cellular phone. The broken lines form no part of the claimed design.
